UNITED STATES PATENT OFFICE

JOHN SYDNEY BARCLAY, OF NEW MALDEN, ENGLAND

HOISTING APPARATUS

Application filed September 30, 1927, Serial No. 223,131, and in Great Britain October 13, 1926.

This invention is for improvements in or relating to hoisting apparatus, and has for an object to provide an improved construction of the same which is particularly adapted for use with boat-lowering and raising gear as used on ships, although the invention is not limited to this particular application.

I provide in hoisting apparatus the combination with a winding drum, and a means for rotating it, of a free-wheel device between them which permits rotation of the drum in the hoisting direction independently of the said means, and a second independent means for rotating the drum in the hoisting direction at a higher speed than does the first said means. The said first mentioned means for rotating the drum comprises a handle or a motor which operates through a speed-reducing gear, and the second mentioned means 20 comprises a handle directly connected to the drum.

The said free-wheel device is located in the interior of the winding drum and comprises a pawl-carrying member secured to a driving 25 shaft and carrying a plurality of pawls adapted to move radially outwards, for example under the action of gravity or centrifugal force, into driving relation with ratchet teeth formed on the inner surface of the winding drum. The handle for rotating the drum is normally maintained out of operative engagement therewith but can be engaged with it, for example by axial movement against a spring, for the purpose of rotating the drum 30 in the hoisting direction.

The pawls are constituted each by a block formed at one end with a rib of cylindrical or semi-cylindrical shape to fit within a correspondingly shaped recess upon the pawl-carrying member and provide a pivotal joint, and at the other end curved cylindrically about the axis of the said pivotal joint to cooperate with a similar face upon the pawl-carrying member to guide the block in its pivotal movements. Each pawl carrying member is keyed on the driving shaft. A drum is provided encircling said member and end plates, whereof at least one is detachable, are secured on said drum to locate it axially with 50 respect to said member. Said end-plates may

also provide bearings for the drum on said shaft.

I also provide a countershaft, a clutch through which it is driven by a motor, a worm gear connecting the countershaft to the drum, and a handle, for the purpose of providing an alternate drive in the case of failure of the power supply, on the countershaft.

A particular embodiment of this invention, as applied to boat-lowering gear for use on ships, will now be described with reference to the accompanying drawings but it is to be understood that this embodiment is described by way of example only.

In the drawings:—

Figure 1 is a front elevation (partly broken away) of a boat-lowering winch.

Figure 2 is a side elevation of the winch looking from the left of Figure 1, and

Figure 3 is a detail view, being a section on the line 3—3 of Figure 1.

Like references indicate like parts throughout the drawings.

The winch mechanism comprises an electric motor 1 which drives through spur gears 2 and 3 and worm gears 4 and 5, the winding drum or barrel 6 whereto the falls are secured. The worm-wheel 5 of the worm gear is keyed to the drum-shaft 8 and the drum 6 is connected to the shaft through a pawl-and-ratchet mechanism hereinafter described which constitutes a free-wheel device; the pawl-and-ratchet are so arranged that the drive is transmitted from the motor 1 to the drum 6 in the hoisting direction, but the drum can overrun the motor in the hoisting direction.

Provision is also made for rotating the drum by means of a suitable handle 7 which can be mounted directly on the drum-shaft 8. This handle is provided in order that the drum may be rotated at a higher speed than is possible with the motor drive, and is particularly intended for rapidly winding in the falls after a boat has been released from them and another boat is required to be lowered. The handle is detachable in order that it may be removed during the lowering operation. For this purpose the handle is made to fit easily upon a reduced end of the drum-

shaft 8 and has formed upon it a hollow boss 9 into which a pin 10 secured to the drum can enter when the handle is fitted on the shaft. By this means the handle can be caused to rotate the drum and is easily detachable therefrom. Alternatively the handle may be mounted on the drum in a manner similar to the starting handle of a motor car engine, that is to say, it is normally free from engagement with the drum but can be moved axially against the action of a spring into engagement with it when it is desired to rotate the drum by hand in the hoisting direction.

A suitable mechanical construction of the free-wheel device aforesaid is illustrated in Figures 1 and 3. In this construction, the drum is formed with open ends (as shown in Figure 1) and has a circumferential rib 11 provided with ratchet teeth 12 around the interior thereof. A pawl-carrying member 13, keyed to the shaft 8 is located within the drum 6 and carries a series of pawls 14. Clamping rings 15 are inserted in the ends of the drums and are drawn together by bolts 16 after the drum and the pawl-carrying member have been assembled on the shaft. These clamping rings are provided with bushes 17 which allow the drum to run freely upon the shaft when it overruns the member 13. They also serve to position the drum accurately with relation to the member 13 and to maintain the pawls 14 in their correct positions. These pawls are provided with rounded ends 18 engaging corresponding recesses in the member 13 which carries them, so as to constitute a pivotal connection, such connection giving the maximum strength against crushing or shearing stresses such as are encountered by the pawl. The forward end of each pawl is curved concentrically with its pivotal axis, and the end wall of the recess is similarly curved to constitute a guide retaining the pawl against movement away from its pivotal axis. The pawls 14 swing radially outwards to engage the ratchet-teeth 12 on the worm-wheel, and this movement is effected automatically either by centrifugal force or by gravity as a pawl comes to the under-side of the worm-wheel, as it is then free to fall into engagement. In the construction illustrated six pawls are used, so that it is ensured that one or more are in the engaging position at all times. It will be obvious, however, that the number of pawls can be varied to suit any particular conditions.

It will be clear from a consideration of Figure 3 that the winding drum can be rotated by the handle 7 in a clockwise direction at a greater speed than that of the pawl-carrying member 13 independently of the latter and that the pawls 14 will automatically engage the ratchet teeth 12 to drive the

drum when the speed of the latter has decreased sufficiently.

This invention is of particular advantage when applied to boat-lowering apparatus, owing to the simplicity of the construction, which conduces to great reliability.

Similarly, all the operations are extremely simple. Thus, for example, if it is desired to lower two or more boats successively from the same davits, the first boat is swung out and lowered in the usual manner under the control of a hand-brake or an automatic centrifugal brake or both (these parts being of any usual or desired construction and therefore not described in detail). During the lowering operation the drum 6 is positively engaged with the hoisting motor 1 by the ratchet and pawl, so that the motor is driven by the falling load, or if desired the motor could be disconnected by a separate clutch as hereinafter described. As soon as the boat has been released it is desired to wind in the falls rapidly in order to lower the second boat. The handle 7 is then applied to or engaged with the winding drum 6 as previously described, so that this operation can be performed at once, and at a higher rate than the motor can do it, owing to the reducing gear which is used between the motor and the winding drum. As soon as the falls have been wound in, the next boat can be swung out and lowered, the only operation required being the removal or disengagement of the winding handle 7.

In the case of hoisting a boat on board, the winding in will be done by means of the motor, and if desired, the handle may also be operated simultaneously for rapidly taking up any slack which may arise.

When electric motors are used on board ship for the hoisting operations, it is desirable to provide an alternative drive, in the case of failure of the power supply, and this is effected in the construction illustrated by providing a handle 20 on the worm shaft as shown in Figure 2.

A clutch is interposed between the spur wheel 3 and the worm shaft 24, whereby the latter can be disconnected from the motor during manual operation, either hoisting or lowering, of the worm shaft. This clutch is conveniently a dog-clutch 21, 22 controlled by a pivoted lever 23. The lever can be moved about its pivot to separate the clutch members 21, 22, so that the shaft can rotate independently of the spur wheel 3. When hoisting, the clutch is retained in its engaging position by the pressure on the teeth. The lever 23 may be interconnected with the main switch or cut-out for the motor in order to ensure that the clutch is engaged whenever power is supplied to the motor.

A second winding drum 6 may be secured to the opposite end of the drum-shaft 8 as shown, and this drum may, if desired, be

fitted with a second free-wheel device similar to that previously described.

Although a particular construction has been described, involving a manual drive as a second means of rotating the drum, it is to be understood that the invention is not limited thereto, for it could equally well be used with other driving means. Also, it will be appreciated that any desired form of free-wheel device which will permit overrunning of the parts in the manner hereinbefore described can be used instead of the particular ratchet-and-pawl mechanism.

I claim:

1. In a hoisting apparatus, the combination with a winding drum and a driving means for rotating it, of a free-wheel device between said winding drum and the said driving means which permits rotation of the drum in the hoisting direction independently of the driving means and a second driving means, independent of the first driving means, for rotating the drum in the hoisting direction at a higher speed than does the first named driving means.

2. In a hoisting apparatus, the combination of a winding drum, driving means for said drum, a free-wheel device between said winding drum and its driving means which permits rotation of the drum in the hoisting direction independently of the said means and manually operable driving means connected to the drum for rotating it in the hoisting direction at a higher speed than does the first said driving means.

3. In a hoisting apparatus, the combination of a winding drum, driving means for said drum, a free-wheel device between said winding drum and its driving means which permits rotation of the drum in the hoisting direction independently of the said means and a handle directly secured to the drum for rotating it in the hoisting direction at a higher speed than does the said driving means.

4. In a hoisting apparatus, the combination of a winding drum, driving means for said drum, a free-wheel device between said winding drum and its driving means which permits rotation of the drum in the hoisting direction independently of the said means, a handle, and means for engaging the handle at will directly with said drum for rotating it in the hoisting direction at a higher speed than does the said driving means.

5. In a hoisting apparatus, the combination of a winding drum, a handle for driving the drum, a second driving means for said drum, a free-wheel device between said winding drum and the second said means which permits rotation of the drum in the hoisting direction independently of the said second means, said free-wheel device being located in the interior of the winding drum and comprising a pawl-carrying member secured to

said second means and carrying a plurality of pawls adapted to swing radially outwards into driving engagement with ratchet teeth formed upon the inner surface of the drum.

6. In a hoisting apparatus, the combination of a winding drum, a handle for driving the drum, a second driving means for said drum, a free-wheel device between said winding drum and the second said means which permits rotation of the drum in the hoisting direction independently of the said second means, said free-wheel device being located in the interior of the winding drum and comprising a pawl-carrying member secured to said second means, and carrying a plurality of pawls adapted to swing radially outwards into driving engagement with ratchet teeth formed upon the inner surface of the drum, each of which pawls is constituted by a block formed at one end with a rib of substantially rounded section to fit within a correspondingly shaped recess in the pawl-carrying member and provide a pivotal joint, and at the other end curved cylindrically about the axis of said pivotal joint to co-operate with a similar face upon the pawl-carrying member to guide the block in its pivotal movements.

7. In a hoisting apparatus, the combination of a winding drum having ratchet teeth formed on its inner surface, an operating handle directly secured to said drum for driving it, a shaft within said drum, a second driving means independent of said operating handle and operatively connected to said shaft, a pawl-carrying member secured on said shaft, pawls carried thereby and adapted to engage the ratchet-teeth aforesaid on said drum, and end plates secured on said drum and engaging axially with the pawl-carrying member.

8. In a hoisting apparatus, the combination of a winding drum having ratchet teeth formed on its inner surface, an operating handle directly secured to said drum for driving it, a shaft within said drum, a second driving means independent of said operating handle and operatively connected to said shaft, a pawl-carrying member secured on said shaft, pawls carried thereby and adapted to engage the ratchet-teeth aforesaid on said drum and detachable end plates rotatable on said shaft, and secured on said drum to provide bearings for it on said shaft.

9. In a hoisting apparatus, the combination of a power-driving shaft, a pinion thereon, a worm-shaft, a gear-wheel meshing with said pinion and freely mounted on said worm-shaft, a clutch between said gear-wheel and the worm-shaft, a winding-shaft, a worm-wheel on said winding shaft driven by the said worm-shaft, a winding-drum, a handle directly secured thereto, a uni-directionally effective clutch between said drum and the

winding shaft and a handle secured to the worm-shaft.

10. In a hoisting apparatus, the combination of a power driving shaft, a pinion thereon, a worm shaft, a gear wheel meshing with said pinion and freely mounted on said worm shaft, a clutch between the said gear wheel and the worm shaft, a winding shaft, a worm wheel on said winding shaft driven by the said worm shaft, a winding drum, a handle directly secured thereto, a pawl and ratchet mechanism effective between said drum and the winding shaft, and a handle secured to the worm shaft.

15. 11. In a hoisting apparatus, the combination of a worm-driving gear, two free-wheel clutches driven thereby, two drums driven respectively through said free-wheel clutches and independent means for directly driving each of said drums.

20. 12. In a hoisting apparatus, the combination of a worm-driving gear, two free-wheel clutches driven thereby, two drums driven respectively through said free-wheel clutches and independent means for directly driving each of said drums, each of said free-wheel clutches comprising a pawl-carrying member located in the interior of and encircled by its respective drum, pawls freely pivoted in said member to swing outwardly into driving engagement with teeth formed on the inner surface of said drum, and end plates secured to said drum to coact with the pawl-carrying member and locate the drum relatively thereto, said end plates also providing bearings for the drum on the drum-driving shaft.

25. 13. In a hoisting apparatus, the combination of a worm-driving gear, a countershaft for driving said gear, driving means connectable to said countershaft through a clutch, a handle secured to said countershaft whereby it can be rotated manually when it is de-clutched from said driving means, two free-wheel clutches driven by said worm-gear, two drums driven respectively through said free-wheel clutches, and independent means for directly driving each of said drums.

30. 14. In a hoisting apparatus, the combination of a worm-driving gear, a plurality of free-wheel clutches driven thereby, drums driven through said free-wheel clutches, and independent means for directly driving each of said drums.

35. 15. In a hoisting apparatus, the combination of a worm-driving gear, a plurality of free-wheel clutches driven thereby, drums driven respectively through said free-wheel clutches, and independent means for separately driving each of said drums.

40. 66. In testimony whereof I affix my signature.
JOHN SYDNEY BARCLAY.
